[57] CLAIM

The ornamental design for a housing for a motorcycle side light, as shown and described.

DESCRIPTION

FIG. 1 is a front elevational view of a housing for a motorcycle side light showing our new design;

FIG. 2 is an end elevational view thereof as seen from the left of FIG. 1;

FIG. 3 is an end elevational view thereof as seen from the right of FIG. 1;

FIG. 4 is a cross-sectional view thereof as taken along line 4—4 of FIG. 1;

FIG. 5 is a top plan view thereof;

FIG. 6 is a bottom plan view thereof;

FIG. 7 is a rear elevational view thereof;

FIG. 8 is a cross-sectional view thereof as taken along line 8—8 of FIG. 1.

FIG. 1.

FIG. 2.

FIG. 3.

FIG. 4.

FIG. 5.

FIG. 6.

FIG. 7.

FIG. 8.
